UNITED STATES PATENT OFFICE.

VINCENT DI PRIMA, OF DETROIT, MICHIGAN.

PISTON-RING FORMER.

Application filed March 31, 1924. Serial No. 703,184.

To all whom it may concern:

Be it known that I, VINCENT DI PRIMA, a citizen of the United States, residing at Detroit, in the county of Wayne and State 5 of Michigan, have invented certain new and useful Improvements in Piston-Ring Formers, of which the following is a specification, reference being had therein to the accompanying drawings.

10 In the manufacture of cast piston rings it is necessary to prepare a mold by using, among other things, pattern rings, and it is essential that the pattern rings be as perfect as possible in order that the cast rings 15 will be as nearly true to required dimensions as possible, to avoid considerable trimming or other machining. The cast piston rings are ordinarily split and to produce the same it has been the practice to set a plug 20 between the ends of a pattern ring to hold the ring to proper size while being fastened to a support or mold board. The use of plugs or interposed members is very unsatisfactory because a pattern ring cannot be held 25 to close dimensions, and as a substitute for such plugs, I have designed an expandable member that may be placed in a pattern ring to maintain the ring expanded to exact dimensions while being fastened to a support 30 or mold board. In consequence of the pattern ring being held to exact dimensions it is obvious that the cast ring may closely approach desired dimensions.

My expandable member includes novel 35 means for expanding it against the inner walls of the pattern ring to the thousandths part of an inch, and it is by virtue of such an expandable member that there may be a uniform production of cast piston rings.

40 My invention will be hereinafter more fully described and then claimed, and reference will now be had to the drawing, wherein—

Figure 1 is a plan of the expandable member set in a pattern piston ring;

45 Fig. 2 is a cross sectional view of the same;

Fig. 3 is a plan of the confronting ends of the expandable member;

50 Fig. 4 is a perspective view showing pattern rings mounted on a mold board;

Fig. 5 is a longitudinal sectional view of a mold with a pattern ring in place;

55 Fig. 6 is a detail view of a modified form of expanding means for the member, and

Fig. 7 is a perspective view of the wedge member shown in Fig. 6.

The reference numeral 1 denotes a pattern ring having a plurality of openings 2 adapted to receive nails 3 or other fastening means whereby the pattern ring may be attached to a mold board 4 or other support, the board 4 being shown with a plurality of patterns thereon adapted to be placed in sand or other molding material 5 to produce grooves in 65 which piston rings may be cast.

To hold the pattern ring 1 to proper dimensions while it is being fastened to the board 4, I employ a comparatively flat annular expandable member 6 having its confronting ends 7 counterbored, as at 8. Adjacent the ends of the annular member 7 are openings 9 for screws 10 or other fastening means employed for connecting the ends of the member 6 by a plate 11 which has 70 slots 12 for the screws 10. On the screws 10 are washers 13 and by tightening the screws the plate 11 may be attached to the ends of the member 6 to hold the member to desired 75 dimensions.

Centrally of the plate 11 is a screw socket 80 14 for a screw 15 having a nut or head 16. The inner end of the screw is provided with a pocket or recess 17 for a ball member 18 which is adapted to seat in the counterbore 85 8 at the confronting ends of the member 6. A suitable form of wrench or key 19 may be placed on the nut or head 16 of the screw 15 to rotate the screw and cause the ball member 18 to expand or distend the confronting ends of the members 6.

Instead of providing the member 6 with a counterbore and using the ball member 18 directly on the member 6, I may provide a 90 wedge member 20, as shown in Figs. 6 and 95 7, and have the ball member 18 engage in the wedge member. I consider the wedge member 20 to be the mechanical equivalent of the ball member 18 or any member that may be interposed between the ends of the 100 expandable member 6 to cause separation of the ends of said member.

With the screws 10 loose and the expandable member 16 set in the pattern ring 1, the 105 screw 15 may be adjusted to expand the member 6 to the thousandths part of an inch, such expansion of the member separating the ends of the pattern ring 1 until the pattern ring approaches a desired configuration and dimension. In practice, I prefer to 110

place marks on the expansible member 6 and the pattern ring 1 so that the pattern ring may be correctly positioned relative to the expansible member 6 to be equally distended at proper places by the expansible member. After the screw 15 is adjusted to bring the pattern ring 1 to proper form, the screws 10 can be tightened to hold the expansible member 6 to its set dimension. The pattern ring 1 can then be fastened to the mold board 4 and the expansible member 6 used for holding other pattern rings to form, so that there will be uniformity in the production of cast piston rings in a mold.

15 With the plate 11 adjustable relative to the ends of the member 6 it is obvious that my expansible member may be used in the production of piston rings of various sizes, and while in the drawing there is illustrated 29 the preferred embodiment of my invention, it is to be understood that the structural elements are susceptible to such variations and modifications as fall within the scope of the appended claims.

25 What I claim is:—

1. Means for adjusting and holding a pat-

tern piston ring to form while being attached to a support for the production of cast piston rings, comprising an expansible member adapted to be placed in a pattern ring and expanded against the inner wall of the pattern ring, said expansible member having counterbored ends, a ball member engaging the counterbored ends of said member, a plate articulating the ends of said member, and means on said plate engaging said ball member to cause expansion of said expansible member.

2. Means for adjusting and holding a pattern piston ring to form while being attached to a support for the production of cast piston rings, comprising an expansible member adapted to be placed in a pattern ring and expanded against the inner wall of the pattern ring, a plate carried by said expansible member, means carried by said plate for expanding said member, and means holding said plate relative to said member to permit of said plate being fixed after said member has been expanded.

In testimony whereof I affix my signature.

VINCENT DI PRIMA.
